(57) **CLAIM**

The ornamental design for an exercise balance pad, as shown and described.

DESCRIPTION

FIG. 1 is a front, top and right side perspective view of an exercise balance pad, showing my new design;
 FIG. 2 is a bottom, front and right side perspective view;
 FIG. 3 is a front elevational view thereof;
 FIG. 4 is a rear elevational view thereof;
 FIG. 5 is a right side elevational view thereof;
 FIG. 6 is a left side elevational view thereof;
 FIG. 7 is a top plan view thereof;
 FIG. 8 is a bottom plan view thereof;
 FIG. 9 is a partial enlarged view of FIG. 1;
 FIG. 10 is a partial enlarged view of FIG. 2;
 FIG. 11 is a partial enlarged view of FIG. 3; and,
 FIG. 12 is a partial enlarged view of FIG. 7.
